INVENTOR,

Clarendon G. Warner,

BY *J. J. DeLancey*

ATTORNEY.

UNITED STATES PATENT OFFICE

CLARENDON G. WARNER, OF HOLYOKE, MASSACHUSETTS.

BOILER.

1,239,546.

Specification of Letters Patent. Patented Sept. 11, 1917.

Application filed June 21, 1916. Serial No. 105,026.

To all whom it may concern:

Be it known that I, CLARENDON G. WARNER, a citizen of the United States of America, and resident of Holyoke, in the 5 county of Hampden and State of Massachusetts, have invented certain new and useful Improvements in Boilers, of which the following is a full, clear, and exact description.

This invention relates to certain new and 10 useful improvements in boilers, and, among other objects, it has for an aim to provide a boiler in which steam may quickly be generated thus adapting the structure for use in connection with a wall paper remover 15 (which adaptation has been illustrated in the drawings), as a water heater in barber shops, and for various other purposes and uses.

The invention is described in conjunction 20 with the accompanying drawings and is set forth in the claim.

In the drawings:—

Figure 1 is substantially a central vertical sectional view through the generator and showing in elevation the heater and the 25 steaming head and its connecting hose.

Fig. 2 is a horizontal sectional view taken on line 2—2, Fig. 1.

Fig. 3 is a central sectional view on a 30 larger scale of the safety device, Fig. 4 being a plan view of the same.

Fig. 5 is a side elevation, on a smaller scale than Fig. 1, showing the external aspect of the incased generator.

In the drawings, A represents the generator 35 which comprises, essentially, the boiler B which preferably is of cylindrical form and is made with an outlet opening or conduit a at its top.

The boiler has at the bottom thereof a 40 depending annular fluid space b formed by the downwardly continued outer wall d of the boiler, the return bent portion e and the upwardly extended portion f, as shown in Fig. 1.

45 The inwardly and upwardly extended portion f at the bottom of the boiler is horizontally continued inwardly and is upwardly reentrant at the portion g to form an inverted dish-shaped cavity at the central portion of the base of the boiler.

D D represent a plurality of pipes, which are open at their opposite ends, and each at its outer end is extended to the inner wall of the said annular space, depending at the bot-

tom of the boiler and in open communication 55 with the main chamber of the boiler.

Each of the said pipes is extended from its connection through the aforesaid wall f more or less nearly horizontally inwardly toward and near the center of the boiler and quite 60 near its bottom; and it is continued upwardly in an approximately vertical limb h and has connection through the bottom wall of the boiler at the central portion g thereof.

As preferably made, the said pipes D D 65 are formed with downwardly and then upwardly return bent portions i i to give increased length in these conduits for circulation and also increased heating surfaces.

F represents a burner or heater of any suitable kind, located beneath the base of the boiler at which the aforesaid pipes D D are provided.

From this burner the water in the boiler is heated to the suitably high temperature 75 for the generation of steam,—the formation of the steam being accelerated by the circulation of the water flowing from the annular space through the convergent pipes D D and upwardly returning into the bottom of the 80 boiler.

The steam when generated to the required pressure is permitted by opening the cock j to pass from the outlet a of the boiler through the flexible hose k to the steaming 85 head G with which the hose at its free end is connected, and which steaming head is moved or operated through means of a pole m pivotally connected thereto and as already known for employment in connection with 90 apparatuses of this character.

The boiler is somewhat widely surrounded by a shell or inclosing casing o between which and the boiler is a completely surrounding air space within which the products of combustion from the burner may be inclosed or in a measure confined for the augmentation of the heating action.

L represents a water gage.

Through suitable supporting parts or connections comprised in the apparatus, the boiler is supported or suspended concentrically within the casing o.

The circular space surrounded by the walls of the inclosed annular space b within the 105 boiler and having the further reentrant central formation, forms, as it were, a trap or retainer for the heat from the burner, or in

other words, a means for the concentration and confinement of the heat to which the pipes D D are subjected; and such formation at the bottom of the boiler is effective for increasing the heating capacity of the boiler, or rendering the latter more easily susceptible to the heating effect.

The boiler is provided at its top with a safety device whereby under a too high pressure of steam the liability of bursting or explosion is obviated.

This device comprises an upwardly open cylindrical casing P having an annular slightly upstanding wall q to form a valve seat surrounding the opening r through the bottom of the casing and which bottom portion of the casing has a screw thread connection with the coupling with which the outlet a and the hose are connected.

20 The said annular valve seat wall q has its position concentrically within the lower portion of the casing P .

R represents a cylindrical weight or gravitational valve which has a close sliding fit within the casing, has the lower portion t thereof of downwardly convergent form, and the base thereof is formed to seat on and normally close said valve seat.

30 By reason of the convergent lower end formation of the weight valve, an annular space u is created between the weight valve and the lower portion of the wall of the casing.

The weight valve R has a plurality of vertical grooves v in its sides which extend from the top of the valve to and terminate at the convergent lower surface portion of the valve and form open communication between the annular space u and the atmosphere to which the top of the casing opens.

Upon the pressure in the boiler becoming too great, and sufficient to overcome the predetermined resistance of the weight valve, the latter is forced from its seat, upwardly, whereupon the steam from the boiler may pass through the uncovered valve seat opening to the annular space u and thence for escape through the vertical grooves or ducts v .

50 *w* represents a bar pivoted on one side of the top of the casing and adapted normally to have a position across the open top of the casing to constitute a stop or means for the limitation of the upward movement of
55 the weight valve.

The valve is provided with a short length of cable or chain x , one end of which is connected to an eye member of the valve, and this constitutes a convenient and easy means for lifting the weight valve out from and clear of the casing, as permitted by the swinging to one side of the pivoted bar, and

as desired to be done at times when the boiler is to have the water supply entered or replenished therewithin.

It is to be especially understood that the principal and most important portion of my present invention resides in a boiler having pipes which are open at both of the ends thereof and which have communication with the interior of the boiler at its outer bottom portion and which extend from such point of communication radially inwardly near the center of the boiler whereat they are upwardly turned and connected into, and for communication with the interior of the boiler; together with a burner, preferably one for liquid fuel combustion, which is located beneath the generator and so arranged and adapted as to have the flame thereof enter between the closely arranged upturned inner end portions of the converged pipes and to impinge directly on said pipes, especially at their inner end portions. 70 75 80

In this apparatus the burner flame, which 85
may be a comparatively narrow or contracted one, is operative upon considerable heating surfaces comprised in the pipes and at the bottom of the burner for quickly and highly heating circulating water, for the 90 production of steam, in a most economical manner.

I claim:—

In combination with an upright casing closed at its top and provided in the latter with draft openings, of a boiler supported within the upper portion of the casing whereby a heater may be arranged beneath the boiler for generating steam therein, said boiler comprising a hollow cylindrical body closed at its top and bottom, the bottom of the boiler having a depending, annular fluid space and concentrically arranged, upwardly depressed center, and a plurality of radially disposed pipes extending horizontally and inwardly from the annular fluid space in proximity and parallel to the bottom of the boiler, the inner end of each pipe terminating in a U-trap which extends below the plane of the lower edge of said annular fluid space, the inner leg of each U-trap extending vertically in a straight line through the upwardly depressed center of the boiler bottom, said U-traps and inner legs being arranged in close relation for direct contact with the heated gases from an underlying heater. 95 100 105 110 115

Signed by me at Springfield, Mass., in presence of two subscribing witnesses.
